MORITZ SCHENKEL, OF BERLIN-CHARLOTTENBURG, GERMANY, ASSIGNOR TO WESTINGHOUSE ELECTRIC & MANUFACTURING COMPANY, A CORPORATION OF PENNSYLVANIA

MERCURY ARC RECTIFIER

Application filed April 23, 1929; Serial No. 357,434, and in Germany April 28, 1928.

My invention relates to means for minimizing backfire in large metal-tank, mercury-arc rectifiers, and it has particular relation to the arrangement of grids in the 5 anode shields of such rectifiers.

Heretofore, it has been the universal practice to enclose the anodes of a multi-anode, metal-tank rectifier in individual protecting sleeves, of tubular shape, which were 10 sometimes slightly restricted in diameter near their lower ends. Various theories as to the functions performed by these anode shields have been held by various investigators. For one thing, the shields help to 15 create an island of more or less quiescent, low-pressure vapor around each anode, as distinguished from the turbulent condition of the vapors in the rest of the tank, accompanied by many sudden gusts or blasts of 20 vapor, of very short time-duration, which must be prevented from reaching the regions of the anodes.

Another function of the anode shield, which may be mentioned, is the deionization 25 of the highly conducting ionized vapor path, in the region of an anode, at the termination of the conducting period of the anode, so that when the arc goes out, the space surrounding the anode will become sufficiently 30 non-conducting soon enough to prevent an arc restriking between that anode as a cathode and another anode in the tank. The exclusion of even momentary vapor-gusts from 35 the region of the anode is for the same purpose of maintaining the insulating quality 40 of the space surrounding each anode during the time when it is negative with respect to the other anodes, the breakdown voltage which this space will withstand being very rapidly lowered with increase in the vapor density in said space.

It is my belief that the slight restrictions 45 which have been found to be necessary at the lower ends of these anode shields have been necessitated in order to more perfectly exclude the sudden blasts of vapor, or waves of vapor pressure, which occur within the tank during the operation of the rectifier.

Heretofore, various grids have been proposed and placed inside of the anode shields.

Usually, one grid has been used in each shield, and it has been either insulated from the shield or in electrical contact thereto. When the grid has been in electrical contact with the shield, it has been necessary to place 55 the grid near the bottom of the shield at some distance below the anode, say about six to seven inches, in order to prevent the grid itself from developing a temporary cathode spot which causes a backfire during 60 the period when its associated anode should be non-conducting. It is my belief that the grid, when so far away from the anode, acts merely mechanically, as a means for preventing transient vapor-pressure blasts from 65 reaching the space under the anode. In other words, a grid placed so far below the anode operates merely to create a quiescent, non-turbulent, low-pressure zone above the 70 grid, so that momentary paths of relatively 70 high vapor-density are not formed between the anode and any other anode of the rectifier during the time when the arc is not playing on the first anode.

Lately, many designers have preferred to 75 mount their grid insulatedly in the respective anode shields. This has added somewhat to the cost and complication of the grid-mounting, but it has enabled the designers to place the grids closer to the anode, 80 say from three-fourths of an inch to two inches below the anodes. In this position, it is my belief that the grids are too close to the anodes to have much effect as a mechanical baffling means for preventing vapor-pressure gusts from reaching the anode. In other words, there is not sufficient space above the grid to establish a zone of 85 quiescent vapors in the immediate vicinity of the anode. However, with this close spacing of the grids, with respect to the anodes, I believe that the grids exercise a strong deionizing effect upon the vapor immediately surrounding the anode, so that the vapor is quickly rendered non-conducting 90 at the end of each arcing period. It is my belief that this electrical function of deionizing the vapor at the surface of the anode 95 is almost entirely absent in the grids which are conductively connected to the shields. 100

because such grids are too far away from the anode to materially affect the ionization of the vapor immediately surrounding the same during the brief time-intervals which 5 are involved in the operation of the rectifier.

According to my present invention, I combine the functions of both types of grids by utilizing an electrically operative deionizing grid placed close to the anode, and a 10 mechanically operative baffling grid placed at some distance from the anode, near the bottom of the anode shield, the spacings of the grids being as previously indicated. The first grid is perfectly insulated from the 15 shield in order to prevent the grid itself from promoting backfire. The second grid need not be insulated and is preferably electrically connected to the shield for facilitating the mechanical mounting of the grid, al- 20 though I do not wish to be limited to the electrical connection of even the bottom grid.

The double arrangement of grids just described is particularly advantageous in rectifiers of very large current-capacities, because, in such cases, it is particularly difficult to obtain a grid which will be effective during the periods of non-conduction of the anode and yet will permit the necessary current flow during the arcing periods. If the 25 spaces provided by the grid are too small, the arc will be restricted to such an extent that the arc current cannot be increased beyond a certain point without enormously 30 increasing the arc drop at this constriction, thereby quickly overheating the grid and producing a backfire. By my provision of two grids, spaced a considerable distance from each other, and segregating the functions 35 of deionization and baffling, so that each grid may be designed for its own particular function, relatively open arc-paths or spaces may be utilized in both grids and the design-limit as to the current capacity 40 of each anode, heretofore encountered in the art, when only one type of grid was utilized, is completely avoided.

Furthermore, by my invention, I am enabled to dispense with the slightly converging restriction at the bottom of the anode shield and may utilize either a straight cylindrical shield or a shield having an outwardly flaring lower end. Each grid increases the voltage-drop in the arc to some 50 extent, but the outwardly flaring lower end of the shield reduces the voltage-drop by removing some of the restriction from the arc path. Hence, by utilizing an anode shield having an outwardly flaring lower end, and 55 protecting that lower end by means of a grid which serves the function of mechanically preventing the vapor-pressure blasts from reaching the anode, and also utilizing an electrically operative, insulated grid dis- 60 posed close to the anode for deionizing the 65

space therearound, I am enabled effectively to shield the anodes of rectifiers of very large capacity, without increasing the voltage drop in the arc beyond the values which have been heretofore obtained in smaller 70 rectifiers.

My invention is shown, by way of illustration, in the accompanying drawing, wherein

Figure 1 is a cross-sectional view of a 75 portion of a metal-tank, mercury-arc rectifier utilizing my special grid arrangement in connection with an anode shield of a common type heretofore used prior to my invention,

Figure 2 is a cross-sectional view of one 80 anode, together with its shield and grids, illustrating a modification, and

Figure 3 is a similar view illustrating a 85 third form of my invention, which is at present my preferred form.

My invention is applicable to any mercury-arc rectifier, but is particularly applicable to a rectifier which is enclosed within a highly evacuated metal tank, a portion 90 of which is shown at 4 in Figure 1. The tank is of the multi-anode type, as will be well understood, only two insulatedly supported anodes 5 and 6 being visible in the fragmentary cross-sectional view of Figure 1.

At the bottom of the tank is an insulated cathode-receptacle, containing liquid mercury 8. It will be understood that suitable 100 electrical connections are provided between the supply and load circuits and the various anodes and cathode, and also that suitable cooling means are provided for the rectifier. My invention does not relate to these common features which are well known and understood to every skilled worker of the art, and hence my drawing and description are confined to the novel features of my 105 rectifier.

Each anode is provided with an insulatedly supported metallic shield 10, having two grids 11 and 12 disposed therein. The upper grid 11 is disposed close under the anode, say from about three-fourths of an 110 inch to about two inches below the anode as previously described, and is insulatedly supported by means of insulators 13. The bottom anode 12 is disposed near the bottom end of the anode shield, say about six inches, or somewhat more below the anode as previously described and may, for convenience, be electrically connected thereto.

In Figure 1, the anode shield 10 is slightly 115 constricted at its lower end, by reason of a converging tapering portion 15.

In Figure 2, the anode shield 10a is of the same diameter throughout its length.

In Figure 3, the anode shield 10b is some- 120 what larger at its lower end, by reason of the outwardly flared portion 17.

Two grids are provided, as above described, in every instance.

The grids may be identical in size and shape, as indicated in Figure 1, or they may 5 be separately designed with a view to their separate functions, as I have outlined above. Thus, in Figure 3, the bottom grid is shown with slightly inclined slats or louvres 19 which are designed for the purpose of more 10 effectively baffling the blasts of mercury-vapor that may impinge thereon.

I claim as my invention:

1. In a multi-anode mercury-arc rectifier, the combination, with each anode, of an 15 insulatingly mounted conductive anode shield having an outwardly flaring lower end terminating in an open mouth, means for deionizing the space within the shield closest to the anode, and a baffling grid extending 20 across the mouth of the shield for impeding the entrance of vapor-pressure blasts.

2. In a multi-anode mercury-arc rectifier, the combination, with each anode, of an insulatingly mounted conductive anode 25 shield having an outwardly flaring lower end terminating in an open mouth at least about six inches below the anode, whereby a quiescent space is produced, and a baffling grid extending across the mouth of the shield for 30 impeding the entrance of vapor-pressure blasts, said baffling grid including means for providing a plurality of passageways therethrough at spaced intervals over the entire area of the grid.

35 3. A metal-tank mercury-arc rectifier characterized by having a plurality of anodes surrounded by individual metallic anode shields having two metallic grids apiece, the top grid being insulatedly supported and being from about three-fourths 40 of an inch to about two inches below the anode, and the lower grid being in electrical contact with the shield and about six inches or more below the anode.

45 In testimony whereof, I have hereunto subscribed my name this 9th day of April, 1929 at Berlin-Siemensstadt, Germany.

MORITZ SCHENKEL.
